(57) **CLAIM**

The ornamental design for a corner pad, as shown and described.

DESCRIPTION

FIG. 1 is a perspective view of our new design.

FIG. 2 is a front view thereof.

FIG. 3 is a side view thereof.

FIG. 4 is a top view thereof; and,

FIG. 5 is a perspective view thereof in a representative unclaimed environment.

The dash-dot lines in the Figures represent unclaimed boundaries of the claimed design. The dash-dash lines in the Figures represent portions and environmental elements that form no part of the claimed design. The ornamentation of the unshaded top surface of the corner pad forms no part of the claimed design.

1 Claim, 5 Drawing Sheets
